(57) **CLAIM**

The ornamental design for a high voltage chopper panel busbar, as shown and described.

DESCRIPTION

FIG. 1 is a perspective view of the front of a high voltage chopper panel busbar;

FIG. 2 is a front side view thereof;

FIG. 3 is a rear side view thereof;

FIG. 4 is a left side view thereof;

FIG. 5 is a right side view thereof;

FIG. 6 is a top side view thereof;

FIG. 7 is a bottom side view thereof; and,

FIG. 8 is a perspective view of the rear side.

The shading and contour lines in FIGS. 1-8 are for illustrative purposes only and form no part of the claimed design. The broken line portion of the figures is included to show unclaimed subject matter only and forms no part of the claimed design.
